ADJUSTABLE HEADPIECE

Gilbert B. Wagenfeld, Philadelphia, Pa.

Application June 17, 1953, Serial No. 362,205

6 Claims. (Cl. 2—197)

1

This invention relates generally to headwear and is more particularly concerned with improvements in a cap of the type which is worn, for example, by those engaged in the dispensing of food and beverages and which simulates in general appearance the well known military overseas cap.

A principal object of the present invention is to provide a cap of the aforementioned type which has a split side the sections of which are arranged for relative swinging movement without an excessive amount of unsightly warping.

Another principal object of the present invention is to provide a cap of the aforementioned type which is adjustable within predetermined limits to fit heads of various shapes and sizes.

And another object of the present invention is to provide such a cap which is simple in design and construction and comparatively simple and inexpensive to manufacture.

Other objects and features of the invention will appear hereinafter.

In the drawings:

Figure 1 is a plan view of a blank of sheet material prepared for the making of a cap embodying the present invention;

Figure 2 is a sectional view taken on line 2—2 of Figure 1;

Figure 3 is a perspective view showing the blank of Figure 1 folded along longitudinally extending lines;

Figure 4 is a perspective view showing the blank of Figure 1 folded along longitudinally extending lines and partly folded along transversely extending lines;

Figure 5 is a side elevational view showing the blank of Figure 1 fully folded into a cap;

Figure 6 is an enlarged sectional elevational view on the line 6—6 of Figure 5;

Figure 7 is a view on line 7—7 of Figure 6, relative movement of the parts, being indicated by broken lines and arrows;

Figure 8 is similar to Figure 7 but shows the parts in detached condition;

Figure 9 is an enlarged fragmentary view at the ridge of the cap where the sections of the split side of the cap meet, one section being turned up for the sake of clarity;

Figure 10 is similar to Figure 9, the relative swinging movement of the sections of the split side of the cap being indicated by broken lines and arrows;

Figure 11 is a sectional elevational view on line 11—11 of Figure 10;

2

Figure 12 is a sectional elevational view on line 12—12 of Figure 10.

Figure 13 is a plan view of another blank prepared for the making of another cap embodying the present invention;

Figure 14 is a sectional view taken on line 14—14 of Figure 13;

Figure 15 is a perspective view showing the blank of Figure 13 folded along longitudinally extending lines;

Figure 16 is a perspective view showing the blank of Figure 13 folded along longitudinally extending lines and partly folded along transversely extending lines;

Figure 17 is a side elevational view showing the blank of Figure 13 fully folded into a cap, the crown thereof, however, being turned wrong side out;

Figure 18 is a sectional view on the line 18—18 of Figure 17;

Figure 19 is similar to Figure 17, but the crown of the cap is turned right side out; and

Figure 20 is a sectional elevational view on the line 20—20 of Figure 19.

Referring particularly to Figure 1, a cap embodying the present invention may be made from a blank of pliable sheet material, such as paper, which is designated generally by the numeral 10. The blank 10 is generally rectangular in shape and includes a facing piece 11 which preferably has adhesively secured to the lower longitudinally extending portion thereof a reinforcing piece 12. The rectangular blank is provided with edges 13 and 14 which extend longitudinally respectively along opposite sides thereof and is further provided with edges 15 and 16 which extend transversely respectively along opposite ends thereof. The square upper opposite end corner portions which would be formed by the edges 13, 15 and 16 extended are cut off as shown respectively along lines 17—18 and 17'—18', and the marginal portion of the blank 10 proximate the edge 13 is coated on one side with an adhesive agent 19, such as glue.

In order to make a cap embodying the present invention from the blank 10, the latter may be folded upon itself along a longitudinally extending score or fold line 20, folded again upon itself in the same direction along a parallel fold line 21 and then folded once more upon itself in the opposite direction along another parallel fold line 22. Referring particularly to Figure 3, when the blank 10 is folded as just described, the fold line 20 extends longitudinally preferably along a line

55 between the points where the edges 15 and 16

respectively meet the edges 17 and 17', the reinforcing piece 12 being embraced and completely concealed by the facing piece 11. In addition, the adhesive coated surface of the marginal portion proximate the edge 13 is exposed to view, and, at opposite ends of the blank 10, the cuts 18 and 18' respectively extend alongside the cuts 17 and 17'.

The opposite end portions of the blank 10 may now be folded upon the same face of the blank 10 respectively along a pair of transversely extending score or fold lines 23 and 24 which are disposed so that in this folded condition (see Figure 5) the terminal portions of the blank 10 overlap. Then the latter are arranged so that (see Figures 5 and 6) the one associated with the edge 15 is disposed in embracing telescoping relation to the one associated with the edge 16, and so that (see Figure 12) the transversely extending marginal portion of the blank 10 proximate the cut 18' and the contiguous portion of the cut 17' is disposed in embracing relation to the transversely extending marginal portion of the blank 10 proximate the cut 18 and the contiguous portion of the cut 17.

Now the terminal portions of the blank 10 may be adjustably secured together. For this purpose there is provided a tab 25 at one lower corner of the blank 10, this tab being formed as shown by a transversely extending cut 26 extending inwardly from the edge 14, and there is further provided in spaced relation to the edge 16 a longitudinally extending slit 27 at the other lower corner of the blank 10. When the tab 25 is engaged in the slit 27 (see Figures 6, 7 and 8), the terminal portions of the blank 10 are adjustably secured together.

The adhesive coated surfaces of the overlapping marginal portions are now pressed together to seal the upper edge portions of the blank and so form the crown ridge of the cap.

There is thus formed an article of headwear which simulates an overseas cap and which comprises a crown part 28 and a head band 29, the former including a pair of side panels 30 and 31, and the side panel 31 including a fore section 32 and an aft section 33. The cap is placed upon the head in conventional manner, and when fitted thereon adjusts itself to the shape and size of the head by reason of the fact that the pair of side panel sections 32 and 33 and their associated portions of the head band are adapted for relative movement, the opposite end portions of the head band being slidably telescopically related, and being secured against excessive movement by the tab 25 engaged in the slit 27.

It is to be noted particularly that the cuts 17 and 17' converge as they approach the ridge of the cap (see Figures 5, 9 and 10), as a consequence of which, when the head band 29 is expanded, the overlapped portions of the panel sections 32 and 33 swing relatively to one another (see Figure 10) with the point of convergence as a pivot center. This action tends to reduce the tendency for the panel sections 32 and 33 to warp due to the expansive movement of the head band 29, as a consequence of which the appearance of the cap is improved. In addition, if desired, the blank 10 may be provided with a fold line 34 close to fold line 21 and extending parallel thereto. The fold line 34 facilitates the telescoping of the terminal portions of the blank 10 one into the other as hereinbefore described.

Referring particularly to Figure 13, a cap embodying the present invention may also be made

from a rectangular blank 35 having a longitudinally extending portion 36, made of open mesh material, such as crinoline, and having another longitudinally extending portion 37 preferably made of paper and comprising a facing piece 38 and a reinforcing piece 39 adhesively secured together so as to firmly hold between corresponding longitudinally extending edges thereof the proximate longitudinally extending edge of the crinoline portion 36. The rectangular unitary blank is provided with edges 40 and 41 which respectively extend longitudinally along opposite sides thereof and is further provided with edges 42 and 43 which extend transversely respectively along opposite ends thereof.

In order to make a cap embodying the present invention from the blank 35, the latter may be folded upon itself along a longitudinally extending score or fold line 44 and then folded again upon itself in the same direction along a parallel fold line 45. With the crinoline portion 36 depending from the paper portion 37 as shown in Figure 15, the opposite end portions of the blank 35 may now be folded upon the same face of the blank respectively along a pair of transversely extending score or fold lines 46 and 47 which are disposed so that in this folded condition (see Figure 17) the terminal portions of the blank 35 overlap. Then the latter are arranged so that (see Figure 18) the paper portion of the folded part terminating in the edge 43 is disposed in embracing telescoping relation to the paper portion of the folded part terminating in the edge 42 is similarly disposed in embracing telescoping relation to the crinoline portion terminating in the edge 43. For facilitating the telescoping of the terminal portions of the blank 35, the latter may be provided with a fold line 48 close to the fold line 45 and extending parallel thereto.

Now the terminal portions of the blank 35 may be adjustably secured together as in the case of the blank 10, there being provided for this purpose a tab 49 and a slit 50, which function in the same manner and for the same purpose as do the corresponding tab and slit in the construction of cap hereinbefore described.

It will be observed that in this condition of the blank 35, the crinoline portion 36 extends below the paper portion 37 as shown in Figures 17 and 18. The corresponding longitudinally extending marginal edges of the overlying portions of the crinoline may now be sewed together, as by the stitches 51, following which the crinoline is turned right side out as shown in Figures 19 and 20 to form the crown part of the cap.

The cap thus formed has a crown part 52 and a head band 53, the former including a pair of side panels 54 and 55, and the side panel 55 including a fore section 56 and an aft section 57. The cap adjusts itself to the size and shape of the head and the opposite end portions of the band are secured against excessive relative movement, all as described hereinbefore with regard to the cap made from the blank 10. It is to be noted, however, that in this second embodiment of the present invention both ends of the blank 35 are cut square, this because the flexible nature of the crinoline eliminates the need for converging cuts, such as 17 and 17' of Figure 1.

It will be understood, of course, that the present invention is susceptible of various changes and modifications which may be made from time to time without involving any departure from the general principles or real spirit thereof, and it is accordingly intended to claim the same broadly,

as well as specifically, as indicated in the appended claims.

What is claimed as new and useful is:

1. A cap of the character described comprising a head band of substantially uniform depth having inwardly folded portions along its opposite longitudinally extending edges, said head band being transversely creased along at least two lines spaced apart less than one half the length of the band and extending normal to the folded edges of the head band to provide the latter with opposite side panels extending from front to rear of the cap, one of said side panels being continuous and the other being split between said crease lines, the split panel being formed of relatively movable head band sections which are telescopically engaged with the folded portions of one section overlapping those of the adjoining section, and a crown part disposed interiorly of said head band, said crown part being substantially coextensive in length with the head band and being extended upwardly from the folded bottom edge of the head band a distance substantially greater than the depth of the head band, said crown part being also creased along lines substantially coincident with the crease lines of the head band to provide the crown part with oppositely disposed continuous and split side panels corresponding to and respectively overlying the inner faces of the head band side panels, the top edges of said oppositely disposed side panels of the crown part being secured together to close the latter along a ridge line extending from front to rear of the cap, the upper corners of the crown part being cut away so as to provide downwardly extending angularly disposed upper side edges, the upper ends of said angularly disposed edges being in registry on the ridge line of the cap and providing an overlapping area in the upper crown part of substantially triangular configuration; whereby to provide for variable expansion of the crown part in the portion thereof extending above the head band.

2. A cap of the character defined in claim 1

having means for adjustably securing together the telescopically engaged relatively movable sections of the head band for varying the effective size of the latter.

5 3. In a cap of the character defined in claim 1 wherein said overlapping portions of the head band are respectively provided with an elongated slit and with a tab of less width than the length of the slit whereby the portion with the tab may be adjusted relatively to that of the slit within the limits of the latter to vary the effective head band size of the cap.

10 4. A cap of the character defined in claim 1 having means for adjustably securing together the telescopically engaged relatively movable sections of the head band for varying the effective size of the latter, said means being incorporated in the inwardly folded top portions of the overlaid sections of the split side panel of the head band.

15 20 5. In a cap of the character defined in claim 1 wherein said crown part is formed of a material of substantially greater flexibility than that of the head band and wherein said head band is faced on at least one of its surfaces with said crown part material.

25 6. In a cap of the character defined in claim 1 wherein said crown part is formed of a material of substantially greater flexibility than that of the head band and is secured to the latter as a lateral extension thereof for the full length of the head band.
